US00D887525S

(12) **United States Design Patent** (10) **Patent No.:** **US D887,525 S**
Huang et al. (45) **Date of Patent:** **** Jun. 16, 2020**

(54) **REEL COMPONENT**

(71) Applicants: **Ben Huang**, Huntington Beach, CA (US); **WINN INCORPORATED**, Huntington Beach, CA (US)

(72) Inventors: **Ben Huang**, Huntington Beach, CA (US); **Elmer S. Alfafara**, Dana Point, CA (US)

(73) Assignee: **Winn Incorporated**, Huntington Beach, CA (US)

(**) Term: **15 Years**

(21) Appl. No.: **29/685,961**

(22) Filed: **Apr. 1, 2019**

Related U.S. Application Data

(62) Division of application No. 29/602,815, filed on May 3, 2017, now Pat. No. Des. 844,744.

(57) **CLAIM**

The ornamental design for a reel component, as shown and described.

DESCRIPTION

FIG. 1 is a front top perspective view of a reel component showing the new design;

FIG. 2 is a rear bottom perspective view thereof;

FIG. 3 is a rear elevational view thereof;

FIG. 4 is a front elevational view thereof;

FIG. 5 is a left elevational view thereof;

FIG. 6 is a right elevational view thereof;

FIG. 7 is a top plan view thereof; and,

FIG. 8 is a bottom plan view thereof.

The dash-dash broken lines in FIGS. 1-8 show portions of the reel component which form no part of the presently claimed design.

1 Claim, 7 Drawing Sheets
